UNITED STATES PATENT OFFICE

HUBERT KRANTZ, OF AACHEN, GERMANY

CENTRIFUGAL EXTRACTOR

Application filed August 18, 1928, Serial No. 300,564, and in Germany February 24, 1928.

This invention relates to centrifugal extractors, and more particularly to extractors of the kind provided with a timing device by which the extractor is automatically stopped 5 after a predetermined time of operation. In the known extractors of this kind the timing device must be set afresh for the desired length of operation before the beginning of each operation.

10 The invention has for its main object to provide a centrifugal extractor the timing device and cooperative parts of which are constructed and arranged in such a manner that the length of operation for which the 15 timing device has once been set is automatically maintained throughout any desired number of successive operations, which means that the attendant need not pay any attention to the timing device before or when 20 starting the extractor for a period of operation corresponding to the preceding operation.

Another object of the invention is to provide a simplified and inexpensive mechanism 25 for starting and stopping the extractor.

Still another object of the invention is the provision of simple and effective means combined with the starting and stopping mechanism for locking the cover in its closed position during the operation of the extractor 30 and allowing the same to be opened only upon the basket drive having been cut out.

An embodiment of the invention is illustrated, by way of example, in the accompanying drawing in which:

Fig. 1 is a fractional side elevation of the extractor, partly in section; Fig. 2 is a plan view with the mechanisms in the position they assume during the operation of the extractor, some parts being in section and some broken away; Fig. 3 is a similar plan view with the mechanisms in the position they assume when the extractor is at rest.

The casing *a* which contains the rotatable basket *b* has attached to it a bracket *c*. A

hand lever 1 is fixed on a shaft 1' which is mounted in the bracket *c* and carries a pinion 2 which engages a rack 3' formed on a bolt 3. This bolt is mounted for limited axial shifting movement in the bracket *c*. The 50 bolt is locked in one of its terminal positions by a latch 4 adapted to engage a notch 3'' of the bolt 3 by a projection 4' and held in locking position by a spring 5. The bolt 3 is surrounded by a spring 6 which bears with one 55 end against a flange 6' of the bolt and with its other end against the bracket *c*. This spring constitutes the stopping and braking power of the controlling mechanism and in the one terminal position of the bolt 3, 60 which is shown in Fig. 2, is held in a compressed condition. The hand lever 1 is connected by a rod 7, a bell crank lever 8 and link 9 with the belt shifter 10 by means of which the driving belt can be shifted from 65 the loose pulley 11 to the fast pulley 12 and vice versa. The hand lever 1 is likewise connected through the bell crank lever 8, a link 13 and a double lever 14 with the brake band 15 of the extractor basket *b*, 16 is the disc of 70 the timing mechanism. The timing mechanism includes a suitable speed reduction gearing (not shown) which is operated by an endless rope 17 from the basket spindle *c'* and through which a slow rotation is imparted to the disc 16. The reduction gearing of the timing device is of such a kind that the disc 16 will make one full revolution for a desired maximum period of operation of the extractor. When it is desired to operate the 75 extractor always at the maximum length of operation, the disc is provided at its periphery with one cam 18. When the operations of the extractor should be shorter, the disc is provided with more cams 18 which are equidistantly fastened on the periphery of the disc. When the period of operation is, for instance, desired to be half the maximum period of 80 operation, the disc is provided with two equally spaced cams, and when it should only 85

90

- be one fourth of the maximum period of operation, it is provided with four equally spaced cams. The cams 18 are designed to co-operate with the nose 4' of the latch 4 for releasing this latch at the end of each period of operation. The cover 19 of the extractor is connected through a link 20 with a pin 21 which is likewise shiftable in the bracket *c* but in a direction transverse to the bolt 3.
- 5 When the extractor is in operation (Fig. 2) the pin 21 bears with its free end against the bolt 3 so that the cover cannot be opened. When the extractor is stopped (Fig. 3), a recess 22 of the bolt 3 comes into registration with the pin 21 so that the same can be moved into this recess and the cover opened. Stops 23, 24, serve to limit the swinging movement of the latch 4 under the action of the spring 5.
- 10 The operation of the device is as follows: It is assumed that the timing device is set for the maximum period of operation, in which case the disc 16 carries only one cam 18 as shown in the drawing. When the extractor is at rest the parts of the controlling mechanism are in the position illustrated by Fig. 3. Before starting the extractor, the cover 19 is closed, whereby the pin 21 is withdrawn from the recess 22 of the bolt 3 so that same is free to be moved while it was up to that time locked against movement by the pin 21. After closing the cover, the hand lever 1 is swung from the full-line position according to Fig. 3 into the full-line position shown in Fig. 2. Thereby the spring 6 is compressed, i. e. it is placed under tension, the latch 4 by its projection 4' engages the notch 3" of the bolt 3 locking the same against movement, the belt shifter 10 moves the driving belt from the loose pulley 11 to the fast pulley 12, and the brake band 15 is released, so that the basket *c* starts rotating and through its spindle *c'* immediately sets the timing device into operation so that the disc 16 begins its rotation. Shortly before the disc terminates its revolution it strikes by its cam 18 against the latch 4 (Fig. 2) and trips the same in such a manner that it releases the bolt 3. The bolt then moves under the action of the spring 6 into the position shown in Fig. 3, causing the driving belt to be moved from the fast pulley 12 to the loose pulley 11 and the brake band 15 to be applied through the intermediary of the gear parts 2, 1, 8, 9, 10, 13, 14. The extractor basket slows down until it comes to a standstill and the cam 18 of the disc 16 simultaneously moves into the starting position of its path of movement, which in the example described is a full circle, i. e. 360°. It is therefore not necessary to set the timing device or disc 16 anew after stopping or before re-starting the extractor, the time of operation for which the disc is set being automatically maintained. If the length of operation of the ex-

tractor should be shorter than the said maximum length of operation, the periphery of the disc 16 is provided with a corresponding number of equally spaced cams 18. The releasing disc at each operation will then rotate through a section corresponding to the distance between two successive cams and then release the latch 4. When the disc 16 carries two cams it will always rotate by

$$\frac{360^\circ}{2} = 180^\circ,$$

75

when it carries three cams it rotates by

$$\frac{360^\circ}{3} = 120^\circ,$$

80

when it carries four cams it rotates by

$$\frac{360^\circ}{4} = 90^\circ,$$

85

and so on. Further changes in the period of operation can be attained by a proper selection of the wheels of the speed reduction gearing of the timing device.

For facilitating the charging and emptying of the extractor basket, it is sometimes desirable to rotate the basket for a short piece *y* hand. To this end, the brake band must be relieved and held in inoperative position. This is done by moving the hand lever 1 from the full-line position into the dot-and-dash-line position 1^a of Fig. 3, this movement being sufficient to relieve the brake band 15. In order to hold the lever 1 in the dot-and-dash-line position the bolt 3 is provided with an opening 25 which in the said position 1^a registers with a pin 26 which is shiftable in the bracket *c* and pushed into the opening 25. The recess 22 of the bolt 3 which is engaged by the pin 21 when the cover is open, is of such a length that it permits the short shifting movement of the bolt 3 caused by the movement of the lever 1 from the full-line position into the position 1^a, Fig. 3. The pin 26 must be withdrawn from the opening 25 before starting the extractor.

In case the extractor is driven by an electromotor the belt shifter 10 is replaced by a switch for the motor. There may also be used instead of the spring 6 a suitably arranged weight or any other power means.

Having thus described my invention, what I claim as new and desire to secure by Letters Patent, is:—

1. In a centrifugal extractor, a rotatable basket, a mechanism for starting and stopping the rotation of the basket, latching means for locking this mechanism during the starting and working of the extractor, power means for automatically moving the said mechanism into stopping position when released, a continuously one way rotatable timing member actuated by the basket drive and designed to make not more than one revolution at each operation of the extractor, at

least one releasing element carried by the timing member for delimiting the amount of rotation of this member and the length of each operation of the extractor, said element being adapted to actuate the said latching means for releasing the starting and stopping mechanism at the end of each section of rotation of the timing member and to assume the starting position of the section of rotation for the succeeding operation.

2. In a centrifugal extractor, a rotatable basket, a timing disc adapted to be slowly rotated by the basket drive, a number of equally spaced cams detachably fastened to the periphery of the timing disc, a mechanism for starting and stopping the rotation of the basket, a latch for locking this mechanism during the starting and working of the extractor, power means for automatically moving the said mechanism into the stopping position when released, the said latch being arranged to project into the path of the cams of the disc and adapted to be tripped into releasing position by one of the cams at the end of each section of rotation of the disc which is determined by the peripheral distance between the cams.

3. In a centrifugal extractor, a rotatable basket, driving means for the basket, a brake for the basket, a controller for the basket driving means, a timing disc adapted to be slowly rotated by the basket drive, a number of equally spaced cams detachably fastened to the periphery of the timing disc and designed to delimit the length of each operation of the extractor, a supporting bracket, a bolt mounted for limited axial shifting movement in this bracket, a spring adapted to be placed under tension when the said bolt is moved into its one terminal position, a latch for locking the bolt in this terminal position, a nose on this latch adapted to be engaged by one of the cams of the timing disc at the end of each section of rotation of the same for tripping the latch to unlock the bolt, a hand lever swingably mounted in the said supporting bracket, operative connecting means between the lever and the controller for the basket driving means and the basket brake, a gearing between the lever and the said bolt designed to move the bolt into the said terminal position and tension the spring when the lever is swung into one of its extreme positions in which it also releases the brake and throws in the basket drive, to hold the lever in this position as long as the said bolt is locked and return the lever into its other extreme position by the action of the said spring when the said bolt is unlocked, thereby cutting out the basket drive and simultaneously applying the basket brake.

4. In a centrifugal extractor, a casing, a cover for the casing, a rotatable basket in the casing, driving means for the basket, a con-

troller for the driving means, a brake for the basket, a timing device actuated by the basket drive and designed to delimit the length of each operation of the extractor, a supporting bracket, a bolt mounted for limited axial shifting movement in the bracket, a spring adapted to be placed under tension when the said bolt is moved into one of its terminal positions, a latch for locking the bolt in this terminal position and adapted to be tripped by the timing device to unlock the bolt at the end of each operation of the extractor, a pin movably connected with the cover and adapted to be held against movement by the said bolt when the same is locked by the said latch, a recess in the said bolt adapted to register with the said pin when the bolt is released by the latch and to receive the pin when the cover is opened, and a swingable hand lever having operative connection with the controller for the basket drive, with the basket brake and with the said bolt and adapted to simultaneously relieve the brake, shift the controller into starting and the bolt into the spring tensioning position when manually swung into one of its extreme positions and to be automatically swung by the said spring into its other extreme position when the bolt is unlocked to cut out the basket drive and apply the brake.

5. In a centrifugal machine of the type embodying a power driven rotating part, a brake for such part, a cover for preventing access to such part, and a lock for the cover, an element connected with the power control, the brake and the cover lock, means for normally influencing a movement of the element to cut out the power, apply the brake and release the cover lock, a member to hold the element against such influencing means, and an automatically repeating timing device to operate the member for release of the element to its influencing means, the timing device being constructed for selectively distinctive timing intervals and serving to automatically repeat said timing intervals without adjustment in successive machine operations.

In testimony whereof I have signed my name to this specification.
